ELECTRICAL CONNECTING DEVICE

Louis W. Cole, New York, and Christopher I. Smith, Sunnyside, Long Island, N. Y., assignors to Cole Electric Products Co. Inc., Long Island City, N. Y., a corporation of New York

Application March 10, 1938, Serial No. 195,034

18 Claims. (Cl. 200—134)

This invention relates to electrical connecting devices and more particularly to electrical connectors intended primarily for the securement of blade terminals such as, for example, the blade terminals of cartridge or similar fuses.

One object of the invention is to provide an electrical connector of the character described constructed and arranged to firmly clamp the blade terminal in secure mechanical and electrical connection therewith.

Another object of the invention is to provide connecting devices of the character described which are of simple and rugged construction and capable of being produced in quantities at low cost.

A further object of the invention is to provide a connector constructed and arranged to be readily secured to the bus bar or similar conductor.

It is also an object of the invention to provide an electrical connector constructed and arranged for the securement thereto of a cable terminal such as, for example, a round cable, in addition to a flat terminal such as the blade terminal of a fuse or the like.

A yet further object of the invention is generally to improve the construction of terminal connectors whereby to provide a good electrical and mechanical connection between the terminal and the connector and between the terminal and the bus bar whereby especially in reference to the fuse terminal which is usually removably connected in position, to substantially eliminate resistance and consequent heating due to loose connections which might otherwise develop.

The above objects of the invention and other objects ancillary thereto will be best understood from the following description considered with reference to the accompanying drawings.

In the drawings:

Fig. 1 is a perspective view of a connector made in accordance with one form of the invention, the connector being shown attached to a bus bar;

Fig. 2 is an end view of the connector, showing, in dotted lines, the blade terminal secured in position;

Fig. 3 is a side view of a connector made in accordance with another form of the invention, the connector being shown secured to the bus bar and having the terminal blade of the fuse secured in position;

Fig. 4 is an end view of the connector shown in Fig. 3;

Fig. 5 is a view similar to Fig. 4 showing a modification of the connector illustrated in Figs. 3 and 4;

Fig. 6 is a top plan view of the connector shown in Fig. 5;

Figs. 7 and 8 are views similar to Figs. 3 and 4 respectively showing another form of the invention;

Fig. 9 is a perspective view of a connector showing yet another form of the invention;

Figs. 10 and 10a are sectional views on the lines

10—10 and 10a—10a respectively of Fig. 9;

Figs. 11 and 12 are perspective views illustrating further embodiments of the invention.

Referring now to the drawings, and first to the form of the invention shown in Figs. 1 and 2, it will be seen that the connector 10 which may be bent substantially into U-shape from a flat strip 15 of suitable metal, preferably copper, comprises as here shown, a base or end wall 14, inclined side wall 16 and an end wall 18. The connector may be mounted on the bus bar B and secured thereto in any suitable way, as by rivets or by screws, as here shown or may be fused to said bus bar. A projection 15 is formed on end wall 14 adjacent side wall 16, preferably by striking the same from said wall. A screw 20 is threaded through end wall 18. The blade 22 (shown in dotted lines) of the fuse engages side wall 16 in face to face relation and is seated on end wall 14 in such a manner that its lower edge engages said end wall and projection 15. End wall 18 confronts and is inclined toward end wall 14, and is also inclined toward side wall 16 forming an acute angle therewith. Said side wall is inclined away from end wall 14 forming an obtuse angle therewith. When screw 20 is threaded down on to blade 22 it forces blade 22 into a close surface engagement with side wall 16 thereby to make good electrical connection therewith. Suitable reinforcing means such as, for example, ribs 28 are provided at the junction of top wall 18 and side wall 16 thereby to strengthen the construction and to prevent side wall 18 from being forced up when screw 20 is threaded down on blade 22. It will be understood that the gage of the metal of which connector 10 is composed is sufficiently high to provide a rigid structure.

The connector 40 illustrated in Figs. 3 and 4 has a side wall 16a and an end wall 18a through which screw 20a is threaded for engaging blade 22. The other end wall 42 is reflexed to provide a base 44 for connection with the bus bar B by bolts 46 provided with nuts 48. Wall 42 is provided with a projection 15a struck up therefrom. The blade 22 of the cartridge fuse F is held in place in the same manner as in the connector 10 illustrated in Figs. 1 and 2, but as here shown,

the fuse is disposed centrally of the bus bar B. The connector 60 illustrated in Figs. 5 and 6 has a curved end wall 62 which obviates the necessity for a projection. The lower edge of 5 the blade 22 is seated in the depression 64 formed by side wall 16a and curved bottom wall 62. In other respects connector 60 is similar to connector 40 shown in Figs. 3 and 4.

The connector 80 illustrated in Figs. 7 and 8 10 may be a casting or forging 82 which has a bore 84 to receive the end of a cable. A threaded bore 86 is provided in the body of the connector through which a screw (not shown) may be threaded to hold the cable in place. The connector 15 is attached to the bus bar B by screws 88. Side wall 90 of the connector is inclined and terminates at one end in an end wall 91 having a short flange 92. Wall 90 terminates at its other end in an end wall 94 through which screw 20 96 is threaded. The lower edge of the blade 22 is positioned and held between side wall 90 and flange 92. Screw 96 holds blade 22 into a close engagement with side wall 90 forming a good electrical connection therewith.

25 In the form of the invention shown in Figs. 9, 10 and 10a, the connector 100 comprises wall 102 and strip 104 secured adjacent each other directly to bus bar B. For this purpose narrower end portions 106 and 108 are projected through 30 an opening 109 in said bar, the shoulders 105 and 107 on wall 102 and strip 104 engaging one surface of said bar and the projected ends of said wall and strip being upset and thereby riveted over the opposite surface of the bar. Strip 104 35 has an end portion 110 which diverges from wall 102 and thereby forms a seat and end wall 111 for one edge of blade 22. The free end portion of wall 102 is bent over seat 111 forming a confronting end wall 112 through which a screw 40 118 is threaded for engagement with the other edge of blade 22 to hold said blade on seat 110 and in good electrical engagement with wall 102. In the modification, shown in Fig. 11, the connector 130 is made out of one piece of metal which 45 is bent into the shape shown, providing short and longer vertical walls 104a and 106a similar to parts 102 and 104 of connector 100 and flat folded portions 132 and 134. Connector 130 may be secured to bus bar B in any suitable way as 50 by one or more bolts 136. End wall 137 confronts end wall and seat 139 and screw 138 is arranged to engage the blade.

The connector 140, shown in Fig. 12, comprises two portions 142 and 144. Portion 142 is bent 55 to provide a side wall 146, inclined end wall 148, and base 150. Member 144 is of such dimensions that when it is fused to base 150 it provides a seat 152 for one edge of the blade 22 (not shown). A screw 154 is threaded through end wall 148 60 and engages the adjacent edge of the blade forcing the same to engage side wall 146. Connector 140 may be secured to bus bar B in any suitable way as by screws or bolts 156.

65 From the foregoing it is apparent that in each of the forms of the invention there is provided a connector which is constructed and arranged to furnish convenient means for securing the blade terminal of a fuse or other electrical conductor. In each of the connectors there is a flat 70 side wall and portions disposed laterally of said side wall, said laterally disposed portions being spaced from each other and arranged in confronting relation, whereby they define with said flat side wall a recess open at one side for the insertion therein of the blade terminal in posi-

tion with one side of the latter in contact with said side wall and with one of its edge portions in engagement with one of said confronting portions of the connector, the other of said confronting portions having openings therethrough and means such as, for example, a screw or the like, adjustably secured in said opening and engageable with the opposite edge portions of the blade terminal for releasably clamping the latter securely in said position. It will be understood, 10 of course, that each connector is made of suitable metal, preferably copper, of sufficient gage to provide a rigid and rugged structure. It will be observed further that in each of the connectors provision is made for obtaining secure, face to face 15 engagement between the blade terminal and the connector, whereby to provide good mechanical and electrical connection therebetween.

Thus it is seen that the constructions herein 20 shown and described are well adapted to accomplish the several objects of the present invention. It will be understood, however, that the invention may be embodied otherwise than as here shown and that in the forms of the invention herein shown or described certain changes in 25 the construction and arrangement of parts may be made and will readily occur to skilled artisans. Therefore, we do not wish to be limited precisely to the present disclosure except as may be required by the appended claims.

Having thus described our invention, what we claim and desire to secure by Letters Patent is:

1. An electrical connector comprising a member having a flat side wall and portions disposed laterally of said side wall, said laterally disposed 35 portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, and means adjustably secured in said opening and engageable with the 45 opposite edge portion of said conductor for releasably clamping the latter in said position.

2. An electrical connector comprising a member having a flat side wall and portions disposed laterally of said side wall, said laterally disposed 50 portions being spaced from each other and arranged in confronting relation defining with said flat side wall a recess open at one side for the insertion therein of a conductor in position with one side of the latter in contact with said side 55 wall and with one of its edge portions in engagement with one of said confronting portions, the other of said confronting portions having an opening therethrough, and means adjustably secured in said opening and engageable with the 60 opposite edge portion of said conductor for releasably clamping the latter in said position, said other confronting portion being inclined toward said side wall whereby said clamping means forces said conductor laterally against said side 65 wall.

3. An electrical connector comprising a member having a flat side wall and portions disposed laterally of said side wall, said laterally disposed 70 portions being spaced from each other and arranged in confronting relation defining with said flat side wall a recess open at one side for the insertion therein of a conductor in position with one side of the latter in contact with said side wall and with one of its edge portions in engage- 75

- ment with one of said confronting portions, the other of said confronting portions having an opening therethrough, and means adjustably secured in said opening and engageable with the opposite edge portion of said conductor for releasably clamping the latter in said position, and means on said first confronting portion for engaging a marginal side edge portion of said conductor to hold the latter against said side wall 10 of the connector.
4. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, and means adjustably secured in said opening and engageable with the opposite edge portions of said conductor for releasably clamping the latter in said position, and means struck up from said first confronting portion for engaging a marginal side edge portion of said conductor to hold the latter against said side wall of the connector.
5. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, and means adjustably secured in said opening and engageable with the opposite edge portion of said conductor for releasably clamping the latter in said position, said side wall and one of said confronting portions having parts of reduced widths providing shoulders for engagement with a bus bar with ends of said parts opposite said shoulders fixed in said bar.
6. An electrical connector comprising a member having a flat side wall and portions disposed laterally of said side wall said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, and means adjustably secured in said opening and engageable with the opposite edge portion of said conductor for releasably clamping the latter in said position, and means for securing one of said laterally disposed portions to a support.
7. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having a part reflexed and provided with means for securing the same to a bus bar.
8. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, and means adjustably secured in said opening and engageable with the opposite edge portions of said conductor for releasably clamping the latter in said position, one of said confronting portions having a part reflexed and provided with means for securing the same to a bus bar, an intermediate portion of said reflexed part being bent to provide a recess to receive the edge portion of said conductor.
9. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, and means adjustably secured in said opening and engageable with the opposite edge portions of said conductor for releasably clamping the latter in said position, one of said confronting portions having a part adjacent said side wall diverging therefrom to provide a recess for the edge portion of the conductor in engagement therewith.
10. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, means adjustably secured in said opening and engageable with the opposite edge portions of said conductor for releasably clamping the latter in said position, and means formed in said connector at one side of said side wall thereof for securing a second conductor terminal therein.
11. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement.

- ment with one of said confronting portions, the other of said confronting portions having an opening therethrough, and means adjustably secured in said opening and engageable with the opposite edge portions of said conductor for releasably clamping the latter in said position, said side wall being inclined outwardly from said first confronting portion, whereby the conductor is biased toward said side wall.
12. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, means adjustably secured in said opening and engageable with the opposite edge portion of said conductor for releasably clamping the latter in said position, and means on said connector for securing the same to a bus bar or other support.
13. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, means adjustably secured in said opening and engageable with the opposite edge portions of said conductor for releasably clamping the latter in said position and means integral with one of said confronting portions for securing the same to a bus bar with the center line of said conductor over the longitudinal center line of said bar.
14. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, the other of said confronting portions having an opening therethrough, and means adjustably secured in said opening and engageable with the opposite edge portions of said conductor for releasably clamping the latter in said position, one of said confronting portions having a part reflexed and provided with means for securing the same to a bus bar, said reflexed part projected laterally of said wall from one side to the other thereof.
15. An electrical connector for a blade terminal, said connector comprising a substantially U-shaped member having a flat side wall and confronting end walls integral therewith, one of said end walls having a part thereof, adjacent said side wall, struck up to provide an abutment for one edge of the blade terminal to hold the latter against said side wall, said other end wall having a threaded opening therein, a screw adjustably secured in said opening and engageable with the opposite edge of said blade terminal, said other end wall being inclined toward said side wall and said screw being similarly inclined whereby the latter forces said blade laterally against said side wall in face to face relation therewith, movement of said blade away from said side wall being prevented by said abutment on the opposite end wall of the connector.
16. An electrical connector for a blade terminal, said connector comprising a substantially U-shaped member having a flat side wall and confronting end walls integral therewith, one of said end walls having a part thereof, adjacent said side wall, struck up to provide an abutment for one edge of the blade terminal to hold the latter against said side wall, said other end wall having a threaded opening therein, a screw adjustably secured in said opening and engageable with the opposite edge of said blade terminal, said other end wall being inclined toward said side wall and said screw being similarly inclined whereby the latter forces said blade laterally against said side wall in face to face relation therewith, movement of said blade away from said side wall being prevented by said abutment on the opposite end wall of the connector and means for reinforcing said inclined end wall at the junction thereof with said side wall.
17. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, and means adjustably mounted on said other confronting portion and engageable with the opposite edge portion of said conductor for releasably clamping the latter in said position.
18. An electrical connector comprising a member having a flat side wall and portions disposed laterally of said side wall, said laterally disposed portions being spaced from each other and arranged in confronting relation defining with said flat side wall a recess open at one side for the insertion therein of a conductor in position with one side of the latter in contact with said side wall and with one of its edge portions in engagement with one of said confronting portions, means adjustably mounted on said other confronting portion and engageable with the opposite edge portion of said conductor for releasably clamping the latter in said position, and means on said first confronting portion for engaging a marginal side edge portion of said conductor to hold the latter against said side wall of the connector.
